UNITED STATES PATENT OFFICE.

YUSUKE TAMAMURA, OF TOKYO-FU, JAPAN.

ROPEWAY CAR.

Application filed December 27, 1922. Serial No. 609,361.

To all whom it may concern:

Be it known that I, YUSUKE TAMAMURA, civil engineer, a subject of His Majesty the Emperor of Japan, residing at No. 18 Gen-bei, Totsuka-machi, Toyotama-gun, Tokyo-fu, Japan, have invented certain new and useful Improvements in Ropeway Cars, of which the following is a specification.

This invention relates to improvements in 10 ropeway cars.

The car according to this invention is composed of three principal elements, the carriage, the clip and the receptacle, each one of which being connected with the remaining 15 two by quadrilaterals. The clip employed in my improved car is a so-called differential clip, such as described in U. S. Patent No. 850,504 patented April 16th, 1907, in the British Patent No. 1565 of 1907 and in the 20 Japanese Patent No. 9896 of December 26th, 1905, all granted to me. It consists of a set of longer and shorter lever-arms, sliding on its own shaft and forming a bisected quadrilateral. The clip engages the hauling rope 25 by means of two sets of couples induced by the action of gravity on the receptacle. The three principal elements, that is to say, the carriage, the clip and the receptacle, all revolve around one main shaft, as the inclination 30 of the ropeway varies. The relative motions of one of the three elements with respect to the remaining two are realized by means of quadrilaterals or bisected quadrilaterals.

35 The principal object of this invention is to obtain a car, in every system of ropeways, which will adapt itself in accordance with the variation of the external conditions by means of automatic displacements of the 40 principal elements, thereby enabling the car to maintain a stable equilibrium all the time. This may be explained more fully as follows:—

45 1. Firstly, whatever may be the system of ropeway used, the car according to this invention causes the clip to engage the hauling rope completely when the car is about to leave a station, developing a gripping force between its jaws sufficient to restrain them 50 from sliding along the rope. On the other hand, upon the arrival at a station the car causes the clip to disengage the said rope promptly.

55 2. Secondly, in any system and in every inclination of ropeway, the car adjusts itself

to a stable position by means of motions of the three principal elements in relation to one another caused by the combined action of the gravity, winds, and shocks. In case of the double rope system, the relative position of the carrying and the hauling ropes are kept normal all the time. The result is that the proportion in which the burden of the load is shared by the two ropes remains practically undisturbed, whereby a perfect 60 balancing of the car is always maintained.

The accompanying drawings illustrate the preferred embodiment of the present invention. In said drawings:

Figure 1 shows a back elevation of my 70 improved car for the double rope system, riding on the side rails at a station.

Figure 2 shows its side elevation.

Figure 3 shows its plan, partly in section.

Figure 4 shows the plan of the part of the 75 clip partly in section.

Figure 5 shows a back elevation of my improved car for the double rope system approaching the rope supporting apparatus mounted upon one of the standards. 80

Figure 6 shows the side view of the car represented in Figure 5.

Figures 7 to 9 show a modification of my invention as applied to a car for the single rope system, being its back elevation, side 85 view and plan respectively.

The car for the double rope system is the typical form of my invention and that for the single rope system is a simple modification of the former. In case of the single rope 90 it combines in itself the properties of both the carrying and the hauling rope. The arrangement in a single rope system is substantially the same as that in the double rope system, for the principal elements of the car 95 in either case correspond to one another.

Referring now more particularly to the drawings, Figures 1 to 3 show the positions assumed by my improved car for the double rope system at the starting point of a station. On the main suspension rail 1 ride a pair of wheels 6 which are mounted for rotary movement upon the axes 7 fixed to the carriage 8. At the central portion of the carriage 8 is fixed a sliding box 9 having a 100 vertically extending aperture on each of the four lateral sides. Within the sliding box 9 is provided a central slider 10 and a pair of lateral sliders 11, the latter being situated on opposite sides of the central slider 10. 105

Through the lower portion of the central slider 10 which is constructed in the form of the letter H, extends a carriage shaft 12 at each end of which is provided a side wheel 14. Between the carriage 8 and the rear side wheel 14, the carriage shaft 12 is formed into an upward projection 13. A pin 16 running through the aperture of the end wall of the sliding box 9 connects each of the lateral sliders 11 with a trunnion upon which a hook bar 17 is mounted. The lateral slider 11, pin 16, trunnion 15 and the hook bar 17 thus form an universal joint.

The clip consists of a pair of longer lever-arms 19 and a pair of shorter lever-arms 20, the heads of which are formed into the clip-jaws 18 to engage the hauling rope 5. Those clip-jaws operate on the head shaft 21 which is formed of two parts that screw into each other as shown in Figure 4. The eye of the head shaft 21 is connected rotatably to the hook bar 17 by means of a pin 23. In this manner a parallelogram is formed by the hook bars 17.

On the main shaft 24 are revolvably mounted the suspension rod 25 of the receptacle 28, the supporting arm 29 of the side wheels 14 and the rear holder 30 for the tail pivot of the longer lever-arms 19. The fore part of the main shaft 24 is formed into a crank head 31 on which the tail pivot of the shorter lever-arms 20 is rotatably mounted. To the suspension rod 25 are connected a pair of suspension hooks 26 to the lower ends of which is connected the bail 27 holding the receptacle 28.

The supporting bars 32, 32 which constitute a parallelogram are pivotally connected at their upper ends with the projection 13 of the carriage shaft 12 and at their lower ends with the forward projection of the supporting arm 29.

At the starting point of a station, in either system of ropeways, the car riding on the main rail 1 has to change its direction of motion from a horizontal to an incline. In consequence thereof the main rail 1 at this point must form a bent path 2 consisting of a curved portion and an incline. When a car passes along such a bent path 2, its forward wheel 6 travels along the incline of the main rail, while the main shaft 24 in the single rope system or the carriage shaft 12 in the double rope system will proceed horizontally along the side rails or rail 3. Therefore, the axis of the rear wheel 6 will describe an arc of an ellipse and the straight lines along which the axis of the forward wheel and the main shaft 24 or carriage shaft 12 respectively travel constitute the diameters of the said ellipse. The double rope system the wheels 6 run on the upper side of the bent path 2, while in the single rope system the wheels 6 roll along the under-side of the corresponding bent path 2.

When leaving a station, the car will rush on to the bent path 2 by its own inertia, thereby the inclined rail 2 pressing on the wheels 6 forces the shaft 21 of the clip to become parallel to the hauling rope 5. In the case of the double rope system, as the car travels along the inclined portion of the bent path 2, the clip will grip the hauling rope. When the hauling rope is so gripped, the car will undergo an angular movement because of the traction of the hauling rope 5, as shown in Figure 5. Such change from the position indicated in Fig. 1 to the angular position (Figure 5) is effected by an abrupt swing of the supporting bars 32 and the hook bars 17, the central slider 10 and the lateral sliders 11 displacing upwards in the sliding box 9, allowing the carriage for a moment to remain stationary until the traction of the hauling rope draws the connecting members 32 and 17 out to their full lengths substantially at right angle to the main support and hauling cable.

The ropeway is so constructed that the distance between the carrying rope 4 or the incline of the bent path 2 and the hauling rope 5 is narrower than normal at the starting point of a station and is gradually widened until it becomes normal at the point where the connecting members 32 and 17 will become perpendicular to the ropes as the car progresses. When the car resumes the angular position the carrying rope will share a due proportion of the load with the hauling rope.

From the starting point of a station to the point where the connecting members 32 and 17 become perpendicular to the ropes, in the double rope system, the wheels 6 entirely lose their carrying function, the hauling rope 5 carries the total load and the whole arrangement presents the appearance of a single rope system. In the single rope system the wheels 6 which are slideable along the supporting rod 32 are pressed down by the inclined part of the bent rail 2. The pressure downward of the inclined part of the bent rail 2 on the wheels 6 causes the hauling rope to press the clip upward with equal force. Hence the stronger the pressure downward of the bent and inclined rail, the greater will be the pressure upward of the hauling rope. Without such pressure upwards the clip will not grip the rope 5. Thus it will be seen that there is no essential difference between the single and double rope systems.

On arriving at a station, the car according to my invention is supported by means of side rails. The clip is at the same time pulled down by the hauling rope 5, whereby the jaws 18 are opened, releasing the hauling rope. In case of the double rope system bent path 2 is necessary at the arriving point at a station, but in single rope system,

because of the absence of the main rail 1 such bent path 2 is not necessary. In other words, in double rope systems, the bent path 2 must be provided both at the entrance and the exit, while in the single rope system it is provided at the exit only.

In Figures 7 to 9 is shown a modification of my improved car constructed for the use of the single rope system. In this car, on its arrival at a station, the side wheels 14 are supported by a single side rail 3. Thus the point of suspension of the car system is shifted from the rope 5 to the side rail 3 and consequently the center of gravity of the receptacle 28 is displaced from the vertical line passing through the rope 5 to that passing through the rail 3. In order to recover such displacement of the center of gravity, a downward pressure must be exerted by the rail 2 on the wheels 6 which is provided at a greater distance from the side wheels 14 than the distance between the clip and the latter. For this purpose the jaws 18 and the carriage 8 which is on the opposite side of the side wheels 14, are pivotally connected by means of a pair of hook bars 17, the carriage being slidably mounted on the supporting bar 32. Moreover, the vertical distance of the carriage 8 from the jaws 18 and its horizontal distance from the side wheels must practically remain constant. A pair of hook bars 17 which connect the carriage with the head shaft 21, forms in combination with the shorter lever-arms 20 a bisected quadrilateral, thereby connecting the carriage with the two remaining principal elements.

In single rope system because of absence of the carrying rope, the pair of the side wheels 14 will be subjected to random oscillations around the main shaft 24 whenever liberated from the side rail 3, unless some means were specially provided to avoid such oscillations. As such means, another bisected quadrilateral is provided connecting the supporting arm 29 with the clip, the said bisected quadrilateral comprising the working bar 33 rigidly fixed on the supporting arm 29 and the connecting bar 34 pivotally connected to the compression bar 35 the working bar 33 and the connecting bar 34 being pivotally connected to each other. Because of the compression spring 37 provided on the rod 36 which is an extension of the rear holder 30, the set of the above mentioned three bars is in a folded position normally and the side wheels 14 are in parallel relation to the head shaft 21. On arriving at a station, because of the coming into contact of one at first and then two of the side wheels 14 with the side rail 3 the supporting arm 29 will be displaced out of the parallel relation with respect to the head shaft 21 against the action of the compression spring 37. On departing from a station, the

set of the side wheels 14 together with the supporting arm 29 will regain their normal position parallel to the head axis 21 by the action of the compression spring 37. In this manner, the danger of collision of the wheels 14 with the rollers mounted on the rope supporting apparatus is avoided.

Having now particularly described and ascertained the nature of my said invention and in what manner the same is to be performed, I declare that what I claim is:

1. A ropeway car, comprising a carriage, a clip and a receptacle and means for interconnecting the said members in such a way that they will adjust themselves relatively to each other to maintain the internal dynamical equilibrium as the external conditions vary, said means including a main shaft about which all said three members are angularly movable and a quadrilateral interconnecting the three members.

2. A ropeway car, comprising a carriage, a clip, a receptacle, means for interconnecting the said members in such a way that they will adjust themselves relatively to each other to maintain the internal equilibrium as the external conditions vary, said means including a main shaft about which all said three members are angularly movable and a quadrilateral interconnecting the three members, and means automatically operative to effect gripping and releasing of the hauling rope by the clip, including wheels in the carriage and an auxiliary rail disposed in the path of the carriage wheels.

3. In a double rope system, the combination of a car including a carriage, a clip and a receptacle, wheels in alignment in the direction of travel at opposite ends of the car, a central slide on the carriage movable in up and down direction, slides on opposite sides of said slide in the direction of travel and independently movable parallel to said slide, a shaft passing through the central slide, auxiliary wheels at opposite ends of the shaft, and auxiliary rails in the path of travel of said auxiliary wheels.

4. Apparatus according to claim 3 including a shaft, a support therefor and parallel motion members pivotally connected at their upper ends on the first shaft and in axial alignment therewith and connected at their lower ends to said support.

5. Apparatus according to claim 3 including arms pivotally connected at their upper ends to said slides respectively and at their lower ends to the opposite ends of a shaft defining a pivot for the two members of the clip, said arms constituting a quadrilateral.

6. Apparatus according to claim 4 including arms pivotally connected at their upper ends to said slides respectively and at their lower ends to the opposite ends of a pivot member for the two members of the clip,

the long and short arms of the clip being pivotally supported on the second shaft, said arms constituting a quadrilateral to normally maintain the said pivot member 5 in parallelism with the carriage.

7. A ropeway car, comprising a carriage, a clip having a short and a long arm and a pivot member therefor and a quadrilateral comprising two arms pivotally connected 10 at their upper ends to the carriage at opposite sides of the vertical longitudinal center thereof and at their lower ends to the opposite ends of said pivot member.

8. Apparatus according to claim 7 including a shaft extending in the plane of relative movement of the arms of the clip, means on said shaft affording pivotal connection to the said arms, and means in the path of travel of the carriage for acting upon the 20 said shaft to vary the relative position of the arms of the clip.

9. Apparatus according to claim 8 including wheels on the carriage and auxiliary

rails in the path of travel thereof for acting upon the said shaft.

10. In a ropeway car, a differential clip having rope-engaging jaws and arms of different length, means pivotally interconnecting the arms intermediate their ends, a shaft extending substantially in the plane of relative movement of the arms, separate means on the shaft pivotally connected to the arms, a carriage, a quadrilateral comprising arms pivotally connected at their upper ends with the carriage at points thereof spaced in the direction of its length and connected at their lower ends to the opposite ends of the means pivotally interconnecting the arms of the clip, and means in the path of movement of the carriage 40 for acting upon the said shaft for varying the relative position of the arms of the clip.

In testimony whereof I affix my signature.

YUSUKE TAMAMURA.
